(57) **CLAIM**

The ornamental design for a brushguard, as shown and described.

DESCRIPTION

FIG. 1 is a perspective view of a brushguard showing our new design;

FIG. 2 is a right side view thereof;

FIG. 3 is a top view thereof;

FIG. 4 is a front view thereof;

FIG. 5 is a bottom view thereof; and,

FIG. 6 is a rear view thereof.

The broken lines shown in the FIGS. 1, 2, 4 and 6 drawing views are for illustrative purposes only and form no part of the claim design.
